UNITED STATES PATENT OFFICE.

EDWARD F. GEIGER, OF DULUTH, MINNESOTA.

SECONDARY ELECTRIC CLOCK.

1,121,347.

Specification of Letters Patent. Patented Dec. 15, 1914.

Application filed January 31, 1914. Serial No. 815,679.

To all whom it may concern:

Be it known that I, EDWARD F. GEIGER, a citizen of the United States, residing at Duluth, in the county of St. Louis and State of Minnesota, have invented certain new and useful Improvements in Secondary Electric Clocks; and I do hereby declare the following to be a full, clear, and exact description of the invention, such as will enable others skilled in the art to which it appertains to make and use the same.

My invention has for its object to provide a simple and efficient electro-mechanical movement adapted for general use to produce step by step rotary motion, and to such ends, generally stated, the invention consists of the novel devices and combination of devices hereinafter described and defined in the claims. A motion producing device of the character above indicated, is especially adapted for use in secondary clocks of electric clock systems, wherein the hands of the secondary clock are moved forward at regular intervals; and the said devices are also well adapted for use in self-winding clocks wherein the main spring is re-wound at regular intervals. In accordance with my invention I utilize the pull of an electro-magnet to displace a pendulum-like propelling lever from a neutral point of suspension, thereby storing up potential energy in the displaced lever, and then utilizing the momentum or inertia of the said lever under backward swinging movement to neutral position, to impart the step by step intermittent movement to a rotary element of the secondary clock or other mechanism operated by the device.

In carrying out the broad idea of my invention, I provide a two-part propelling lever, or, otherwise stated, I provide primary and secondary propelling levers so arranged that in swinging from the neutral position of suspension, the secondary lever will cause a movement of the primary lever and the primary lever is free to swing on after the secondary lever has reached the limit of its displacement, but with the said primary lever arranged on return swinging movement to neutral position, to impart an operative movement to the secondary lever, exerting thereon all of the potential energy stored up on the said primary propelling lever.

One embodiment of the invention is illustrated in the single view of drawings, which

shows portions of the master clock together with the electric circuit containing the same.

Of the parts of the master clock, it is only necessary to note the escapement wheel 1 which carries electrical contacts 2, and the pendulum 3 which carries escapement pallets 4 and an electric contact 5. The escapement wheel 1 has sixty teeth, and in the arrangement illustrated, is shown as provided with two diametrically opposite contacts 2 that are adapted to be alternately and intermittently engaged with the contact 5 which is carried by the pendulum 3. The said pendulum 3 is pivoted at 6. The electric contact 5, as shown, is secured to the head 7 of the pendulum, and is adapted to be adjusted by a set screw 8 applied to the end of an arm 9 which is also secured to the said pendulum head 7.

Of the parts of the secondary clock, the numeral 10 indicates a shaft that is connected to the ordinary change gear of the clock. This change shaft 10 carries a spur gear 11 that meshes with a spur pinion 12 that is secured to rotate with the propelling wheel 13 of the said secondary clock. This propelling wheel 13 has sixty teeth, and in the arrangement illustrated, the gear 11 has twice as many teeth as the pinion 12, so that the change gear shaft 10 will be given one rotation for each two rotations of the propelling wheel 13. The teeth of the propelling wheel 13 are, as shown, engaged by three gravity-held dogs 14, 15 and 16, that are pivoted to suitable supports not shown. The propelling wheel is arranged to rotate in the direction of the arrow marked thereon, and the dog 14 prevents backward rotations thereof, while the dogs 15 and 16 operate as lock dogs, normally preventing forward rotation of the said wheel. The lock dogs 15 and 16, at their free ends, have laterally projecting pins 17 and 18, respectively, that are adapted to be alternately engaged by the ends of the releasing bar 19, that is carried by the lower end of a propelling bar 20, which latter is suspended from pivots at its upper end 20^a. A pendulum-like weighted arm 21, is provided with a weighted lower end, and at its upper end, is pivotally suspended at 21^a from the intermediate portion of the propelling bar 20, and normally engages with a stop pin, stud or projection 22 carried by the lower end of the said propelling bar.

The numeral 23 indicates a driving dog

which is pivoted to the propelling bar 20 and engages with the teeth of the propelling wheel 13. An armature 24, which is secured to the propelling bar 20, is subject to a relatively fixed electro-magnet 25. For the purpose of this case, it may be assumed that the contact 5 which is carried by the pendulum of the master clock, is insulated therefrom and from other metallic parts 10 of the master clock mechanism.

The numeral 26 indicates a wire that is extended from the master clock contact 5 to one terminal of the electro-magnet 25, and the numeral 26 indicates another wire 15 which is extended from the other terminal of the said electro-magnet, and through metallic parts of the master clock mechanism, is connected to the contacts 2 thereof. The numeral 27 indicates a battery or source of 20 electrical energy interposed in the said circuit between the master clock and the electro-magnet of the secondary clock, which circuit may, of course, be of any desired length, and constitutes what may be designated 25 as the controlling circuit.

With the above described arrangement, it is evident that the controlling circuit will be closed intermittently and for very short intervals of time, to-wit, while the contact 5 30 is in engagement with one or the other of the contacts 2 of the master clock. The escapement wheel 1 of the master clock makes one rotation each minute, and consequently, the above noted contact and closing of the controlling circuit will occur every half minute.

Whenever the controlling circuit is closed, as just described, the magnet 25 of the secondary clock will, of course, be energized, it will attract the armature 24 and swing the 40 complete or two-part propelling lever of the said secondary clock toward the right in respect to the drawing. Movement of the propelling lever 20 toward the right will primarily accomplish three things; namely, release of the pawl, or lock dog 15, from the engagement of the toothed wheel 13 and the dropping of pawl, or lock dog 16 upon the teeth of the propelling wheel 13 so as to allow a rotation of one space to said propelling wheel, and engagement of the driving dog 23 with another tooth at the right on the said propelling lever wheel. But this swinging movement of the said propelling lever to the right, of course, carries with it the 50 weighted arm 20. When the armature 24 engages the core of the magnet 25, the propelling lever 20 will be stopped, but the weighted arm 21 is free to swing toward the right until its momentum is overcome by 60 gravity.

About the time that the movement of the weight arm toward the right is thus overcome by gravity, the contact 5 of the master clock will, by a swinging movement of the 65 pendulum 3 of the master clock toward the

right, be carried out of engagement with the aligned contact 2, so that the controlling circuit will be opened and the magnet 25 de-energized. When the weight arm 21 swings back toward the left it strikes the stop 22 on the propelling bar 20, and by virtue of its weight and momentum, exerts a force amply strong to insure the desired step of movement of the controlling wheel 13 in the direction of the arrow. In fact, in this way, 70 nearly the entire energy of the short electrical impulse is rendered effective to drive the propelling wheel of the secondary clock.

Movement of the propelling lever toward the left, imparts movement to the propelling wheel 13 through bar 19, releases the lock dog 16 and drops the lock dog 15 back into operative position, and thus, prevents the propelling wheel from being moved more than one tooth in the direction of the 85 arrow. Preferably, the arrangement is such that the propelling lever in moving toward the left, moves into its lowest position. One or the other of the lock dogs 15—16 will always be operative to prevent over rotation 90 of the propelling wheel 13. The pivoted bar 20 and weighted arm 21 constitute a two-part propelling lever. Also in a very proper sense and for the sake of definition, the lever 21 may be treated as a primary 95 propelling lever, and the bar or lever 20 as a secondary propelling lever.

In the construction illustrated, the change gear shaft 10 of the secondary clock, which should be given one rotation each minute, 100 or one rotation for each rotation of the escapement wheel 1 of the master clock, is, as noted, given one rotation for each two rotations of the propelling wheel 13, and hence, the said propelling wheel must be moved 105 two toothed spaces each minute. For this reason, the two diametrically opposite contacts 2 are carried by the escapement wheel of the master clock. This is a desirable arrangement for large clocks, but for comparatively small clocks, the propelling wheel 13 of the secondary clock, may be directly connected to the change gear shaft, and, in this instance, the escapement wheel of the master clock would require but one contact 110 2. On the other hand, if the change gear shaft of the secondary clock should be geared to the propelling wheel thereof, for rotation at the rate of one to four, then the escapement wheel of the master clock should have four contacts set on quarters. As is evident, one contact carried by the escapement wheel of the master clock would cause the secondary clock to be operated every minute, and moved forward one minute; 115 and two contacts carried thereby would cause the secondary clock to be operated every half minute and moved forward one half minute and four contacts would cause the said secondary clock to be operated every 120 125 130

quarter minute and moved forward one fourth minute.

One or both of the lock dogs 15—16 are very desirable in relatively large clocks, but in comparatively small clocks, they might, in some instances, be dispensed with. Furthermore, the device is noiseless in its operation and moves without shocks.

In the specification and certain of the 10 claims, a statement is made that the lock dogs engage teeth of the propelling wheel of the secondary clock. This statement is used in a broad and liberal sense.

What I claim is:

- 15 1. In a mechanism for producing step by step rotary motion, the combination with a propelling wheel, of a weighted primary propelling lever suspended like a pendulum, a dog-equipped secondary propelling lever, said primary lever being free to swing in one direction only from normal position in respect to said secondary lever, and means for intermittently moving said secondary lever so as to force said 20 weighted primary lever from its neutral position, and render the same, under return movement, operative on said secondary lever to cause the dog thereof to impart a step of rotary movement to said propelling wheel.
- 25 2. In a mechanism for producing step by step rotary motion, the combination with a propelling wheel, of a weighted primary propelling lever suspended like a pendulum, a dog-equipped secondary propelling lever, said primary lever being free to swing in one direction only from normal position in respect to said secondary lever, means for intermittently moving said secondary lever so as to force said weighted primary lever 30 from its neutral position, and render the same, under return movement, operative on said secondary lever to cause the dog thereof to impart a step of rotary movement to said propelling wheel.
- 35 3. In a mechanism for producing step by step rotary motion, the combination with a propelling wheel, of a weighted primary propelling lever suspended like a pendulum, a dog-equipped secondary propelling lever, said primary lever being free to swing in one direction only from normal position in respect to said secondary lever, means for intermittently moving said secondary lever so as to force said weighted primary lever 40 from its neutral position, and render the same, under return movement, operative on said secondary lever to cause the dog thereof to impart a step of rotary movement to said propelling wheel, and means for limiting the angle of action of said dog-equipped secondary lever.
- 45 3. In a mechanism for producing step by step rotary motion, the combination with a toothed propelling wheel, of a weighted primary propelling lever suspended like a pendulum, a dog-equipped secondary propelling lever, said primary lever being free to swing 50
- in one direction only from normal position in respect to said secondary lever, means for intermittently moving said secondary lever 55 so as to force said weighted primary lever from its neutral position, and render the same, under return movement, operative on said secondary lever to cause the dog thereof to impart a step of rotary movement to said propelling wheel, at least one controlling dog operative on said toothed propelling wheel to prevent irregular forward movements thereof, and a member carried by said dog-equipped lever for intermittently releasing said controlling dog for engagement with the teeth of said propelling wheel.
4. In a mechanism for producing step by step rotary motion, the combination with a propelling wheel, of a weighted primary 70 propelling lever suspended like a pendulum, a dog-equipped secondary propelling lever, an armature connected to the latter, said primary lever being free to swing in one direction only from normal position in respect to said secondary lever, a controlling circuit including an electro-magnet operating on said armature to move said secondary lever so as to force said weighted primary lever from its neutral position, and render 75 the same under return movement, operative on said secondary lever, to cause the dog thereof to impart a step of rotary movement to said propelling wheel.
5. In a mechanism for producing step by 80 step rotary motion, the combination with a propelling wheel, of a weight driven dog equipped two-part propelling lever suspended like a pendulum, the sections of which have a relative movement in one direction 85 and means for intermittently moving said propelling lever from a neutral position and for releasing the same, and thereby rendering the dog thereof operative on said propelling wheel to impart a step of rotary 90 movement thereto when the said lever is swung back by gravity from its displaced position to its neutral position.

In testimony whereof I affix my signature in presence of two witnesses.
